A. E. McBRIDE,
COVER FOR HUMIDORS.
APPLICATION FILED JULY 28, 1915.

1,190,311.

Patented July 11, 1916.

INVENTOR

ARTHUR E. McBRIDE

BY *Thomas L. Wilder*

ATTORNEY

UNITED STATES PATENT OFFICE.

ARTHUR E. McBRIDE, OF UTICA, NEW YORK.

COVER FOR HUMIDORS.

1,190,311.

Specification of Letters Patent. Patented July 11, 1916.

Application filed July 28, 1915. Serial No. 42,305.

To all whom it may concern:

Be it known that I, ARTHUR E. McBRIDE, a citizen of the United States, residing at Utica, in the county of Oneida and State of New York, have invented certain new and useful Improvements in Covers for Humidors, of which the following is a specification, reference being had therein to the accompanying drawing.

10 My invention relates to a cover for a humidor, and I declare the following to be a full, clear, concise and exact description thereof sufficient to enable anyone skilled in the art to which it appertains to make and 15 use the same, reference being had to the accompanying drawings in which like reference characters refer to like parts throughout the specification.

The object of the invention is to provide 20 a simple, inexpensive cover for a humidor that will be of service not only in keeping the tobacco in the humidor moist but also may be utilized as a pipe holder and ash tray. Furthermore, the cover can be employed as such or it can be employed as a 25 pipe holder and ash tray independent of the humidor, for it is provided with a standard having a flat base for this purpose.

30 The object will be seen from the drawings in which—

Figure 1 is a perspective view of the cover disposed upon a humidor; Fig. 2 is a fragmentary view of a humidor, showing the 35 cover disposed thereon in reverse position; Fig. 3 is a vertical section of the humidor and cover; Fig. 4 is a detail perspective view of the cover; Fig. 5 is a side elevation of the cover showing a certain modification 40 thereof.

Referring more particularly to the drawings, a humidor of any size or construction and ordinarily made of glass is represented by —1—. The humidor is inclosed at the 45 top by a cover 2. The cover 2 is made preferably of glass and is provided with the annular flange 3 forming the shoulders 4 and 5, adapted for the fitting of the cover 2, with either surface uppermost, upon the top 50 of the humidor —1—. The upper surface of the cover 2, as seen in Fig. 3, is formed with a bowl 15 to provide a receptacle for holding pipes, when not in use, and the ashes therefrom. The lower surface of the 55 cover 2, as seen in that same Fig. 3 is extended downwardly with a more or less

graceful curving surface that terminates in an enlarged annular member 6, having a flat base portion at 7 for resting upon a correspondingly similar surface, when the 60 cover 2 is employed as an ash tray independently of the humidor. An aperture 8 gives access to the recess or chamber 9 formed within the interior of the member 6. A sponge or other absorbent material 10 is 65 disposed within the chamber 9, whereby to humidify the air within the interior of the humidor, when the cover 2 is disposed thereon with the member 6 lowermost. Likewise, 70 when the cover 2 is placed upon the humidor —1— in the reverse position, as illustrated in Fig. 2, the annular member 6 will provide an ornament to beautify the cover, as well as a knob or handle for the manipulation of the same.

In the event that it is thought desirable to employ the cover 2, as an ash tray independent of its use as a cover for the humidor, the lower or base portion 7, furnishes 80 a perfectly flat surface and is so proportioned to the rest of the cover, that it will serve as a stable standard for the purpose.

Fig. 5 shows a modification embodying the notches 11 formed in the ledge 12 of the cover 2 adjacent the bowl 15. The notches 85 11 conform in shape to cross section of cigarettes, cigars and the stems of pipes and are intended for the disposition of the same thereacross, whereby to prevent such cigarettes, cigars and pipes, as may be so laid 90 from rolling about in the bowl 15. It will be readily understood that the cover 2 may be adapted to inclose the top of any size or any form of humidor.

Having thus described my invention 95 what I claim as new and desire to secure by Letters Patent is:

1. In a cover for a humidor, an annular flange, forming shoulders, whereby said cover may be reversibly held upon a humidor, a bowl upon one side of said cover, and means upon the other side for containing moisture, said means forming a standard for said cover.
2. In a cover for a humidor, an annular flange forming shoulders, whereby said cover may be reversibly held upon a humidor, a bowl for holding pipes and ashes upon one side of said cover, an annular member having a chamber for holding moisture, whereby to humidify the air within said humidor upon the other side of

said cover and an aperture for the admission of a sponge into said chamber.

3. In a cover for a humidor, an annular flange, whereby said cover may be reversibly held upon said humidor, notches for holding cigarettes, cigars and pipes upon one side of said cover, and a standard for supporting said cover independent of said humidor.
4. In a cover for a humidor, an annular flange forming shoulders on either side thereto, whereby said cover may be reversi-

bly held upon said humidor, a bowl upon one side of said cover, notches in the periphery of said bowl, an enlarged annular member upon the other side of said cover, said annular member having a flat base, whereby to form a standard, a chamber within said annular member for the disposition of a sponge, and an aperture giving access to said chamber.

In testimony whereof I have affixed my signature.

ARTHUR E. McBRIDE.
